CLAIM

The ornamental design for a cover for a container for small loads (as e.g. vehicle brakes and parts thereof), as shown and described.

DESCRIPTION

FIG. 1 is a top plan view of a cover for a container for small loads (as e.g. vehicle brakes and parts thereof), showing my new design;

FIG. 2 is a left side elevational view thereof, the right side elevational view being a mirror image of the sides shown;

FIG. 3 is an end elevational view thereof, the front elevational view being a mirror image of the rear view shown;

FIG. 4 is a bottom plan view thereof;

FIG. 5 is a sectional view along line V—V of FIG. 4; and,

FIG. 6 is a perspective view.
